Application November 9, 1934, Serial No. 752,270

10 Claims.

(Cl. 15—8)

This invention relates to vacuum cleaners of the type in which the suction fan is rigidly attached to the handle, and separated from the floor tool or suction head, by a swivel joint allowing the handle to be rotated about its own axis. The general object of the invention is to provide, in this type of cleaner, a motor driven rotary agitator in the suction head. Another object is to provide a vacuum cleaner having a motor driven agitator which may be manually adjusted toward or from the carpet by simply lifting or lowering the handle. To the accomplishment of these ends, the invention contemplates the use of a secondary motor mounted directly upon the suction head and independent of the prime mover that drives the suction fan.

Another object is to provide such an arrangement permitting disconnection of the floor tool from the suction neck and detachment of the auxiliary conductor.

Another object is to provide a novel arrangement of suction head with rotary agitator and driving motor, the arrangement being such as to permit the use of a belt drive in which the belt is not twisted whereby a very heavy type of flat belt, capable of long wear and incapable of getting out of adjustment, may be employed.

Another object is to provide suitable means for housing said belt and for preventing the same from carrying dirt from the suction chamber of the floor tool into said housing means.

Another object is to provide a novel and improved means for detachably securing the belt housing cover in place.

A further object is to provide a novel and improved arrangement for ventilation of the agitator drive motor.

Another object is to provide an improved detachable mounting connecting the agitator to the suction head, providing extreme stability of position for the agitator axis without sacrificing the ease with which the agitator may be snapped into or out of the retaining means.

Another object is to provide an improved novel suction head construction, in which a smooth sliding contact with the suspended rug is provided by polished non-corrosive metal lips embracing the lower edges of the front and rear walls of the suction head casting (preferably of aluminum for lightness) so as to avoid undue resistance to the sliding of the suction head over the rug held against it by suction, and wherein the regions of the rug directly beneath the corners of the suction head are depressed out of contact with such corners by the supporting roll-

ers at the rear, and by toe rollers at the front, which effectively prevent any of said corners catching against the rug either during forward or backward movement of the cleaner. In this connection, it is the object also to slightly unseal the rug at the ends and particularly at the corners of the floor tool so as to prevent the undue cutting off of the air flow through the suction head.

In the drawings:

Fig. 1 is a right side elevation of a vacuum cleaner embodying our invention.

Fig. 2 is a plan view of the same.

Fig. 3 is a transverse sectional view through the dust collector.

Fig. 4 is a detail enlarged cross section of a portion of the contiguous walls of the dust collector.

Fig. 5 is a similar view of a modification thereof.

Fig. 5a is a plan view of a section of the paper material used in the inner bag.

Fig. 6 is a front elevation of the floor tool of the cleaner.

Fig. 7 is an inverted plan view of the floor tool.

Fig. 8 is a rear elevation of the floor tool, portions being shown in section.

Fig. 9 is a longitudinal sectional view through the floor tool viewed from the front taken on the line 9—9 of Fig. 15.

Fig. 10 is a cross section through the floor tool taken on the line 10—10 of Fig. 6.

Fig. 11 is the same as Fig. 10 with the exception that the nozzle height adjusting lever and the agitator end bearing are removed.

Fig. 11a is a view similar to Fig. 11 of a modified form of crank axle mounting.

Fig. 12 is a plan view of the left end of the floor tool adjustable support.

Fig. 13 is a horizontal sectional view through the right end of the floor tool adjustable support.

Fig. 14 is a cross section through the floor tool taken on the line 14—14 of Fig. 6.

Fig. 15 is a cross section through the floor tool taken on the line 15—15 of Fig. 6 looking toward the right end of the floor tool.

Fig. 16 is a cross section through the floor tool taken on the line 16—16 of Fig. 6 looking toward the left end of the floor tool.

Fig. 17 is a central cross section through the floor tool taken on the line 17—17 of Fig. 6.

Fig. 18 is a cross section, enlarged, through a portion of the agitator illustrating one of the beater elements and its mounting.

Fig. 19 is a perspective view of one of the beater elements.

Fig. 20 is a longitudinal sectional view through one end region of one of the beater elements.

5 Fig. 21 is a sectional view through the belt housing taken on the line 21-21 of Fig. 14.

Fig. 22 is a cross section through the belt housing taken on the line 22-22 of Fig. 16.

Referring now to Fig. 1 of the drawings, the 10 specific embodiment of our invention therein illustrated comprises a prime mover in the form of an electric motor 10 secured to a fan casing 11 in which is a suction producing fan which draws air into the fan casing 11 through a suction inlet 12 or 12a and a valve chamber 13 controlled by a transparent topped rotatable valve element 14.

In the suction inlet 12 is socketed a suction neck 15. In the suction inlet 12a is socketed a 20 hollow handle 16. To the suction neck 15 and motor 10 a floor tool A is attached by means of a swivel joint and auxiliary conductor B. Below the handle 16 is suspended the dust collector C. Secured to the upper region of the handle 16 is 25 the current supply and controlling mechanism D which includes an extension cord 17 adapted to be attached to a source of current supply. A main conductor 18 is plugged at 19 into the switch assembly 20, extends downwardly between 30 the handle 16 and the dust collector C, and at its other end is connected to the motor 10.

The floor tool A includes a suction head 22, preferably of cast aluminum. The head 22 provides an elongated agitator chamber 23, substantially semi-cylindrical in cross section above the agitator axis "a" (see Fig. 11). Below the plane of the agitator axis "a", the suction chamber is defined between two substantially parallel upright lips 24. The upper region of the suction head in the rear is gradually broadened out from the ends to the center thereof as at 25, merging into a central neck 26 the axis of which extends upwardly and rearwardly (see Fig. 17). Also centered between the ends of the suction head is 45 a flattened region 27 in the top portion of the wall of the head upon which is mounted the housing 28 of the agitator drive motor. Screws 29 extended upwardly through the top wall 27 and threaded into the base of the motor housing 28, secure the same in place. A machined fit between the housing 28 and the top wall 27 makes the joint substantially air tight. The front wall of the central region of the head 22 and the front wall of the motor housing 28 are formed on a 50 continuous curve, and the machined fit joins these curves so as to substantially seal the junction thus adding to the appearance of the floor tool.

The lower region of the suction chamber, 60 defined between the lips 24, provides a space, rectangular in plan, into which the region of the rug directly below the suction chamber may be slightly drawn, into the path of the rotating agitator, and confines the air currents which play 65 around the lower half of the agitator to an upward direction of flow, thereby increasing the efficiency of operation of the agitator. In this connection it may be noted that the agitator rotates in the direction indicated by the arrows 30 70 and the air currents flow as indicated by the arrows 31. Cooperating to secure this result is the tangency of the regions 25 with the curved upper region of the suction chamber 23. The converging regions 25 of the suction head allow 75 the suction in the neck 26 to be impressed sub-

stantially uniformly upon the entire length of the suction chamber.

Referring now to Fig. 9 in conjunction with Fig. 17, the agitator motor comprises the field coils 32 suitably mounted as on bolts 33 in the 5 casing 28, and the armature 34, mounted on the shaft 35 one end of which is journaled in a bearing in one end of the casing 28 and the other end of which is journaled in a belt housing cover 38 is detachably secured to the belt housing rim 36, 10 and forms together with the end of the motor casing 28, a housing for the belt. A partition 39 extends transversely within the casing 28 so as to divide the same into a large chamber in which is located the armature 34 and fields 32 15 and a smaller chamber from which air is drawn by the fan 40 mounted on the shaft 35. Air enters this small chamber through ventilation openings 41 in the casing 28, and leaves the large chamber through ventilation openings 42 in the 20 casing 28. The opening 43 in which the fan 40 revolves is of about the same diameter as the armature 34 so that the air stream leaving the fan 40 is concentrated on the space between the armature and the fields. The circulation of air 25 through the motor is strengthened by the suction in the suction chamber 23, impressed against the far end of the large chamber in the motor housing through an opening 44 extending through both the top wall 27 of the suction head and the 30 bottom wall of the housing 28. The opening 44 is located beyond the far side of the field coils 32 so as to assist in the creation of air flow axially between the armature and field coils. Where the discharge openings 42 are present, the actual 35 function of the suction opening 44 is to reduce any pressure within the motor casing that may be built up by the resistance of the end wall thereof to the air current propelled by the fan so that the fan 40 does not have to overcome this resistance in discharging the air currents through the 40 openings 42.

The rotary agitator comprises a hub 45 preferably of cast aluminum the ends of which are recessed as at 46 to receive the ends of the bearing caps 47. Secured in the latter are bushings 48 of an oil saturated metal material and the axle studs 49 of the agitator are journaled in the bushings 48. The axle studs 49 are pressed into the ends of the hub 45.

The bearing caps 47 are mounted in channels 50 formed in the ends of the suction head, and are secured in seating relation with said channels by spring clips 51. The side arms of the clip 51 embrace the area defined by channel 50 55 and are formed with arched portions 52 to engage the bearing cap and diverging end portions 53 to receive the bearing cap when the same is being inserted and to cause the arms to spring apart when the bearing cap is pressed upwardly there- 60 against. The upper ends of the recesses 50 are semi-circular as at 54 and the arched portions 52 hold the bearing caps securely seated against these semi-circular shoulders 54. The side shoulders of the recess 50 prevent the agitator from 65 being displaced either forwardly or backwardly and the shoulder 54 prevents the agitator from being displaced upwardly to any appreciable extent. Accordingly, no matter what might be contacted by the agitator during rotation, it would 70 be impossible for the agitator to be moved out of its axis of rotation. It is thereby assured that there is no possibility of the agitator assuming a position where the beater elements can contact any portion of the suction head or where the 75

drive belt will rub against any fixed portion of the apparatus or where cleaning efficiency would be impaired. The position of the agitator axis relative to the suction mouth is rigidly fixed so that the most delicate adjustments of the agitator relative to the rug may be made by varying the height of the floor tool. The clips 51 are secured in sockets 51a formed in the ends of the floor tool by means of rivets 51b.

10 Intermediate its ends the hub 45 is formed with a pulley 55, aligned with the belt housing 36. Secured to the end of the shaft 35 is a drive pulley 56. A flat belt 57 connects the pulleys 55 and 56 and extends through an opening 58 in the top wall 27 of the suction head. The belt housing cover 38 has its edges machined to fit tightly against the case 28 and the top wall 27 except for the restricted opening 59 which may be formed either in the edge of the cover 38 or in 15 the top wall 27. The opening 59 is directly opposite the reaches of the belt 57 where they pass through the opening 58. The area within the opening 58 between the reaches of the belt 57 is closed by a plate 60 having an up bent ear 61 20 secured by rivets 62 to the cover plate 38. A pair of lugs 63 punched out of the ear 61 engage bosses 64 formed in the cover plate 38 (see Fig. 22) so as to securely position the plate 60.

30 A spring clip 65 secured to the cover plate 38 is adapted to impress the head of a post 66 secured to the belt housing 36 so as to hold the cover plate in place. A pair of pins 67 (Figs. 15, 16, and 21) secured in the cover plate, engage in corresponding recesses 68 formed in the belt housing 36 so as to properly position the cover 38.

35 Air currents flowing through the opening 59, induced by the suction within the suction chamber, will impinge against and follow down along the reaches of the belt 57 as indicated by the 40 arrows 69 so as to prevent the belt from carrying dirt from the suction chamber up into the belt housing. Only one opening 59 is employed and this opening is positioned opposite the upwardly moving reach of the belt. The other reach will 45 produce enough movement of air through the opening through which it enters the suction housing so as to effectively prevent passage of any dirt through this opening without the aid of an exterior air inlet at this point. Thus the loss of 50 suction caused by the auxiliary air inlet is reduced to a minimum and the air current which is induced by suction is concentrated at the point where it operates to the utmost efficiency in 55 achieving the desired result. This air jet not only prevents the belt from carrying dirt into the belt housing but also prevents dirt from being thrown into the belt housing from the rotary agitator. The likelihood of dirt being thrown 60 into the belt housing by the agitator through the opening is slight because of the fact that said other opening is not above the upwardly moving point on the agitator and is not normal to any line of throw from the tips of the agitator elements.

65 Mounted in the hub 45 are the agitating elements some of which comprise brushes 70 and others of which comprise beaters 71. These agitating elements are mounted in recesses 72 (Fig. 70 16) in the hub and are secured by means of set screws 73 threaded through ears 74 formed in the hub and projecting slightly beyond the periphery thereof, the heads of the screws 73 being partially received in recesses 75 in the hub (Fig. 75 18). Viewing the agitator from the direction of

its right end as in Fig. 16, each set screw 73 is located on the right side of the element which it secures. This facilitates the ready removal or replacement of agitator elements as rotation of the agitator will bring each screw head successively into line with the operator's screw driver.

5 The resilient beater element 71 (Figs. 18, 19, and 20) comprises a strip of rubber 76 one side of which is vulcanized into the beater strip or channel 77 and the other side of which is vulcanized into the backing channel 78. The rubber is bonded to these channels by a known process of bonding metal to rubber and we find that under the most rigorous conditions of service these beaters will hold up for an indefinite period. 10 The rubber is of a very high grade high percentage gum content, very tough and very flexible. The strip can be bent double without any injury whatever to the beater. The backing channel 78 is secured in one of the slots 72, 20 its edges substantially flush with the surface of the hub, and the beater strip 77 is separated from the hub by a substantial width of the rubber strip 76 so that as the beater contacts a suspended rug during rotation it will yield so as to 25 cushion the blow as indicated in Fig. 17.

A lug 79, upstruck from the bottom of the channel 78, is molded into the base of the strip 76, and fills the space between the side walls of the channel in line with the axis of the set 30 screw 73. The lug 79 transmits the pressure of the set screw 73 from one side wall to the other of the channel thus preventing collapsing of the channel under the pressure of the set screw and assuring that the beater element will not fly 35 out of or work out of position in its socket, as would happen if the channel were not thus reinforced. This lug aids also in giving additional retention of the rubber strip in the channel.

40 The ends of the floor tool are formed with wheel sockets 80 which accommodate the supporting wheels 81, the toe rollers 82, and the agitator bearing channels 50. The supporting wheels 81 are journaled upon the crank throws 83 (see Fig. 8) of a crankshaft 84 extending just 45 beneath the region 25 of the suction head. Downwardly opening slots 85 (Fig. 11) in the inner walls of the rearwardly projecting portions of the wheel sockets 81, accommodate the crank-shaft 84 and allow the crankshaft and wheel 50 assembly to be inserted as a unit or to be removed for servicing and repair. In the preferred form of the invention, the crankshaft is journaled in bearing brackets 86 secured by means of screws 87 to the rear wall 24 of the suction head. The 55 brackets 86 are placed in position on the shaft portion of the crankshaft 84 prior to the securing of the ends of the latter by means of pins 88 into the disk of the offset portions 89 of the crank throws 83. The brackets 86 rest against the inner wall of the sockets 80. The disks 89 slidingly engage the inner surfaces of said inner walls, bridging across the slots 85, so as to accurately position the wheels 81 spaced from all walls of the sockets. An adjusting lever 90 is secured to the shaft 84 near one end. Its end is formed with a socket 91 (Fig. 8) in which a coil spring is pinned between one end of the socket and a shoulder 93 on a sliding latch pin 94. The latter engages selectively a series of openings 95 (Fig. 70 10) in a quadrant 96 secured by means of rivets 97 (Fig. 8) to one of the sockets 80. The quadrant 96 is L-shaped in cross section so as to provide a one-quarter cylindrical portion to engage against the rounded upper surface of the 75

socket 80 and the down-turned flanged portions in which are formed the openings 95. A scale plate 98 is secured to the wheel socket 80 and has indicating characters 99 to locate the several positions of adjustment. Oscillation of the crank-shaft 84 will raise or lower the wheels 81 relative to the suction head thus causing the latter to be bodily raised or lowered relative to the supporting surface, and consequently adjusting both 10 the agitator and the mouth of the floor tool to the rug.

In Fig. 11a we have shown a modified form of the mounting in which the slots 85a are made to snugly receive the shaft 84 and in which the 15 shaft 84 is held snugly against the upper extremity of the slot 85a by means of a bracket or latch element 86a.

The rug R is lifted from the floor by the suction in the suction head and suspended against 20 the smooth curved lower surfaces of the lips 100, and between passages of the beating elements will become arched into the suction chamber. The vibration of the raised portion of the rug which is produced by successive blows of the beating 25 element will throw the embedded grit up into the air stream, and the beating and brushing elements, rotating forwardly in the lower regions of their orbits, will direct the air stream and the dirt particles first forwardly, thence upwardly, 30 and thence rearwardly, as indicated by the arrows 31, the dirt particles being impelled into the region 25 of the suction head at substantially a tangent to the cylindrical path which has been followed in rising from the rug.

35 The neck 26 is provided with an insert 101 formed with an outwardly extending annular threaded flange 102, and the suction neck 15 has an out-turned flange 103 held in rotatable engagement with the flange 102 by a flanged 40 nut 104. A stud 105 is riveted in the wall of the neck 15 closely adjacent the nut 104, and at the bottom of the nut. The stud 105 is adapted to engage against the side arms 106 (Fig. 14) of a yoke 107 which arches above the neck 15 in 45 a plane which intersects the stud 105. The side arms 106 are secured by screws 108 to the side regions of the neck 26 and against lugs 109 formed in the neck 26, by means of which the yoke is rigidly held in correct position.

50 The agitator motor is supplied with current through the auxiliary conductor 110 one end of which is provided with a socket plug 111 which is plugged into a socket 112 secured to the side of the motor 10. The socket 112 is positioned 55 substantially midway between the lateral and front regions of the motor 10 so that the conductor 110 may project from the socket 112 in a straight line which is tangent to the broad curve J which it makes in half-looping around the neck 60 15 (Fig. 2).

The socket 112 is connected in parallel within the dome of the motor 10 to the respective wires of the conductor 18 which carry current to the motor 10 from the switch 20.

65 The arch in the curve J is just sufficient to allow the handle and fan assembly to be rotated 90° beyond its normal position shown in Fig. 2 in a counter-clockwise direction in which the conductor will be wrapped more snugly around 70 the neck 15. The stud 105 will thence engage the yoke 107 so as to prevent further movement. The position of the plug 112 is such that the conductor 110 adjacent the plug will always remain tangent to the curve J, and so that no bending strain will be placed upon the conductor 75

when it is pulled around the neck 15 to the extreme position just described. The end of the conductor which enters the agitator motor is also arranged so that no undue bending of the conductor will occur at this point. The conductor is made as short as possible so that it will not unduly project to catch against objects during cleaning operations. The stopping of the rotation at 90° either side of center insures against the plug 111 becoming accidentally pulled out of 10 its socket.

The dust collector comprises the inner bag 114 of porous paper having a reinforced neck 115 which is engaged in a coupling member 116 mounted in the fan discharge outlet 117. The 15 bag 114 is of a rough creped porous paper, a section of the surface of which is illustrated in Fig. 5a, and which is illustrated in cross section in Figs. 4 and 5. This bag is rectangular in shape and snugly fits within the cover 118 which has a 20 longitudinal mouth extending from end to end of its upper region, defined between the separable portions 119 of the side walls of the cover. The upper edges of these side walls are stiffened as at 120 and are provided with end studs 121 detachably engaged by brackets 122 and 123. They are spaced apart when in place as shown in Fig. 3 to form the mouth 124. The cover 118 according to the present invention instead of being formed of knitted textile material or woven cloth 30 as has been the former practice, is made of an impregnated fabric or composition material which is impervious to air.

The floor tool is provided with bumpers 135 and 140, the former encircling the mouth of the 35 suction head, and the latter, the motor casing 28. The bumper 135 is of novel construction in that instead of being faced with a continuous strip of metal, as in prior structures, it is provided with washer inserts 136, bonded to the rubber in 40 registry with openings 137 through which screws 138 are threaded into the walls 24 and sockets 80, as shown in Figs. 6, 7, and 17.

In the operation of the cleaner, the handle 16 is grasped by the operator and lifted slightly. 45 Since it is rigid with the fan casing, the latter will be lifted also, lifting the rear rollers E from the floor. The cleaner is operated with the rollers E thus out of contact, and the operator may thence vary the spacing of the agitator and suction head mouth from the floor and vary the vigor of beating by raising or lowering the handle, during operation. In securing this result, the presence of resilient beaters in the combination is an advantage, as they permit of a greater range 50 of spacing of the agitator axis from the rug in which beating may be performed. This is a decided advantage over that type of cleaner in which the only possible adjustment is secured by a change in the floor tool mounting adjustment. 60

We claim:

1. In a suction cleaner, a suction producing unit including a prime mover, a floor tool attached to said unit, a rotary agitator in said floor tool, an auxiliary electric motor mounted upon the top 65 of said floor tool with its axis parallel to the axis of said agitator, a drive pulley at one end of said motor, a casing covering said motor, a belt housing cover on the end of the casing, closed thereagainst and extending to the top wall of the 70 floor tool, an opening in said wall, below said belt housing, a driven pulley on said agitator below said opening, a belt travelling on said pulleys and extending through said opening and an air inlet between the lower end of said belt hous- 75

- ing and said top wall, opposite the upwardly moving reach of said belt.
2. In a suction cleaner, a suction producing unit including a prime mover, a floor tool attached to said unit, a rotary agitator in said floor tool, an auxiliary electric motor mounted upon the top of said floor tool with its axis parallel to the axis of said agitator, means whereby said agitator is driven from said auxiliary motor, said motor including field windings and an armature, a casing covering said motor, an air inlet opening in one end of the casing, and an outlet opening directly connecting the space in the opposite end of the casing with the suction chamber in the floor tool, through said top wall.
3. In a suction cleaner, a suction head formed integrally with rigid vertical channels in its end walls, a rotary agitator, shaft ends projecting from the ends thereof, a pair of bearing bushings loosely mounted on the respective shaft ends, said bushings being received in said channels and removable therefrom by sliding the agitator bodily downwardly, each bushing being in substantial contact simultaneously with both sides 25 of its respective channel and spring detent means engaging the rounded side faces of said bushings and retaining them in the channels.
4. In a suction cleaner, a suction producing unit including a prime mover, a floor tool attached to said unit, a rotary agitator in said floor tool, an auxiliary electric motor mounted upon the top of said floor tool with its axis parallel to the axis of said agitator, a drive pulley at one end of said motor, a belt housing on the end of the motor, 30 closed thereagainst and extending to the top wall of the floor tool, coacting latching elements on the inner face of said belt housing and on the end of the motor, positioned substantially centrally of said belt housing, coacting positioning means on the housing and motor respectively, loosely engaging each other, an opening in said wall, below said belt housing, a driven pulley on said agitator below said opening, and a belt travelling on said pulleys and extending through said opening.
5. In a suction cleaner, a suction head formed integrally with rigid vertical channels in its end walls, a rotary agitator, shaft ends projecting from the ends of said agitator, bearings rotatably 35 mounted on the respective shaft ends, said bearings having portions received in said channels and removable therefrom by sliding the agitator bodily downwardly, and spring detent means engaging lateral regions of said portions and retaining them in the channels, said channels having at their upper ends shoulders against which said bushings seat so as to rigidly hold said agitator against being moved upwardly out of correct position when operating against a rug.
6. In a suction cleaner, a floor tool, a rotary agitator therein, an electric motor mounted upon the top of said floor tool with its axis parallel to the axis of said agitator, a drive pulley at one end of said motor, a casing covering said motor, 40 a belt housing cover on the end of the casing closed thereagainst and extending to the top wall of the floor tool, an opening in said wall, below said belt housing, a driven pulley on said agitator below said opening, a belt travelling on said pulleys and extending through said open-
- ing and an air inlet between the lower end of said belt housing and said top wall.
7. In a suction cleaner, a floor tool, a rotary agitator therein, an electric motor mounted upon the top of said floor tool with its axis parallel 5 to the axis of said agitator, a drive pulley at one end of said motor, a casing covering said motor, a belt housing cover on the end of the casing, closed thereagainst and extending to the top wall of the floor tool, coacting latching elements on the inner face of said belt housing and on the end of the motor, coacting positioning means on the housing and motor respectively, engaging each other, an opening in said wall, below said belt housing, a driven pulley on said agitator below said opening, and a belt travelling on said pulleys and extending through said opening.
8. In a suction cleaner, a floor tool, a rotary agitator therein, an electric motor mounted upon the top of said floor tool with its axis parallel 20 to the axis of said agitator, a drive pulley at one end of said motor, a casing covering said motor, a belt housing cover on the end of the casing, closed thereagainst and extending to the top wall of the floor tool, coacting latching elements 25 on the inner face of said belt housing and on the end of the motor, an opening in said wall, below said belt housing, a driven pulley on said agitator below said opening, and a belt travelling on said pulleys and extending through said opening.
9. In a suction cleaner, a floor tool, an electric motor mounted on said floor tool with its axis parallel to the longitudinal axis on the floor tool, said motor having a drive pulley projecting from one end, a casing covering said motor, an 30 opening in the floor tool below said drive pulley, a rotating agitator revolvably mounted in the floor tool, a driven pulley on such agitator located below said opening, a belt travelling on said pulleys and extending thru said opening, said 35 floor tool having a cleaning mouth at its bottom, and said agitator being detachably mounted and removable bodily thru said mouth, said belt being detachable by the act of dropping its upper region thru said opening and thence dropping 40 the belt and agitator together downwardly thru said mouth, and being attachable by a reverse process, and a belt cover attachable to the end of said casing and forming therewith when attached, a housing completely enclosing that portion of the belt which projects above the top of the floor tool, said cover being detachable so as to expose all of said portion extending above the top of the floor tool for manipulation thereof.
10. In a suction cleaner, a floor tool, a rotary 45 agitator therein, an electric motor mounted upon the top of said floor tool with its axis parallel to the axis of said agitator, a drive pulley at one end of said motor, a casing over said motor, a belt housing cover on the end of the 50 motor casing, closed thereagainst and extending to the top wall of the floor tool, coacting latching elements on said belt housing and on the end of the motor, an opening in said wall, below said belt housing, a driven pulley on said 55 agitator below said opening, and a belt travelling on said pulleys and extending through said opening.
